(57) **CLAIM**

The ornamental design for a drawing board, as shown and described.

DESCRIPTION

FIG. 1 is a perspective view of the drawing board; FIG. 2 is a front view of the drawing board; FIG. 3 is a left side view of the drawing board; FIG. 4 is a right side view of the drawing board; FIG. 5 is a top view of the drawing board; and, FIG. 6 is a bottom view of the drawing board. The broken lines in the drawings are included to show portions of the drawing board that form no part of the claimed design.

1 Claim, 6 Drawing Sheets
